PERSONALIZED FILLER CAP

Sidney Sherman and Charles Sherman, Baltimore, Md.

Application February 14, 1957, Serial No. 44,870

Term of patent 14 years

(Cl. D91—1)

Fig. 1.

Fig. 2.

Fig. 3.

Fig. 1 is a plan view of the personalized filler cap embodying our new design;

Fig. 2 is a rear view thereof; and

Fig. 3 is a side view thereof.

The dominant features of our design reside in those portions shown in full lines.

We claim:

The ornamental design for a personalized filler cap, as shown and described.
